LOOM LAY REBOUND CONTROL
MECHANISMJohn D. Watson, Appleton, and Ludwig
Andersen, Wauwatosa, Wis.

Application November 12, 1934, Serial No. 752,583

11 Claims. (Cl. 139—190)

This invention relates to improvements in loom lay rebound control mechanisms, particularly adapted for use in connection with Fourdrinier wire cloth weaving looms.

During the weaving of Fourdrinier wire cloth on a loom, it has heretofore been customary to beat up the filler wires with two blows. The first blow, which is a heavy blow and accomplished with the shed either partially or fully open, operates to drive the shute or weft wire into knuckles formed in the warp and at the same time this initial blow crimps the shute or weft wire to form a proper mesh. After the warp or sheds have been crossed over there is a second relatively light blow which insures proper retention of position of the weft wire, as said weft wire has a tendency to spring away from the warp knuckles after the first heavy blow. As a result of this procedure there is, in the finished cloth, a possibility of there being high shots or rough marks. There is also, by virtue of the above procedure, a constant tendency of the shute wire to turn over which requires the forming of new crimps which will obviously detract from the life and quality of the finished cloth.

It is, therefore the primary object of the present invention to provide a mechanism for Fourdrinier wire cloth weaving looms which will so control the rebound of the lay from the shute wire after the first blow as to render a second blow unnecessary, whereby the finished cloth will be more desirable and have a more perfect surface than was possible of attainment heretofore.

A further object of the invention is to provide a mechanism of the character described which controls the lay or beater of a loom in a manner so that when the lay drops and the reed beats against the face of the cloth, the mechanism can block or limit rebound and hold the reed against the face of the cloth until the sheds cross over, whereby turning or moving of the weft wire is prevented.

A further object of the invention is to provide a mechanism of the character described where-
5 in rebound can be eliminated or controlled to a desired extent or be changed to a plurality of short vibrations.

A further object of the invention is to provide a loom lay rebound control mechanism which 50 can easily be incorporated with a standard Fourdrinier wire cloth weaving loom with a minimum of modification to the latter.

A further object of the invention is to provide a loom lay rebound control mechanism which 55 is efficient, expeditious and automatic in its opera-

tion, which is inexpensive to manufacture and install, which is strong and durable, and which is well adapted for the purposes described.

With the above and other objects in view the invention consists of the improved loom lay rebound control mechanism, and its parts and combinations as set forth in the claims, and all equivalents thereof.

In the drawings in which the same reference characters indicate the same parts in all of the views:

Fig. 1 is a fragmentary side view, partly in section, of that portion of a Fourdrinier wire cloth weaving loom with which the improved lay rebound control mechanism is associated;

Fig. 2 is a plan view of the showing in Fig. 1 with the heddle frames and wire omitted;

Fig. 3 is a fragmentary sectional view showing a crossed position of the heddle frames and warp wires with respect to the relative positions of the same illustrated in Fig. 1;

Fig. 4 is an enlarged detail vertical sectional view of the rebound control hydraulic dash pot;

Fig. 5 is an enlarged fragmentary detail sectional view of a portion of the dash pot and certain valve mechanism;

Fig. 6 is an enlarged detail sectional view taken on line 6—6 of Fig. 4; and

Fig. 7 is an enlarged fragmentary detailed sectional view illustrating certain valve mechanism.

The portion of a Fourdrinier wire cloth weaving loom with which the invention is associated is illustrated in the drawings and it will be seen to comprise a lay 8 suitably movably supported by arms 9. The lay 8 is provided with an opening 10 therethrough for the accommodation of warp wires 11. The lay also carries, adjacent the opening 10, and in proximity to the warp wires 11, a reed 12 which is resiliently mounted in the lay against rubber cushioning blocks 13.

The warp wires 11 extend from a source over a supporting and guiding member 14 and are extended through reciprocatory heddle frames 15. The heddle frames are reciprocated by chains 16 extending to a source of power (not shown) and are adapted during the operation of the mechanism to move the warp wires from the position in Fig. 1 to a crossed over position, as in Fig. 3, and vice versa. As before mentioned said warp wires extend through the opening 10

in the lay and immediately adjacent the pocket formed by said warp wires a shute or weft wire 17 is adapted to be forced into said pocket. The woven wire cloth 18 extends from this point out-

55

wardly and is adapted to be fed over a supporting member 19.

The mechanism further includes a driven shaft 20 which is connected with and driven by a source 5 of power (not shown). Mounted on said shaft is a large cam 21 along whose surface a roller 22 on the outer end of a lever 23 rides. The other end of said lever is keyed to a rocker shaft 24 which shaft also has mounted fast thereon 10 the inner ends of levers 25. The other ends of said levers 25 are pivotally connected with end portions of links 26, and the other end portions of said links are pivotally connected with ears 27 projecting from inner face portions of the 15 lay 8.

From the description thus far, it is believed that it will be evident that as the shaft 20 is turned, the lever 23 following said cam, will transmit rocking motion to the rocking shaft 24. This 20 will cause the levers 25 to rock, and through the links 26 reciprocating movement will be imparted to the lay 8 to effect its withdrawal, and when the high point on cam 21 passes the roller 31, the lay falls forward due to gravity. This 25 action, of course, takes place while the other loom mechanism is operating, including the shute (not shown) for the disposition of the shute wires 17, and the heddle frames carrying the warp wires 11. Suffice it to say that the various movements 30 are effective to cause the reed 12 to engage the shute wires and force the same into proper relative position with respect to the crossed or angled warp wires.

It is at this stage that the standard Fourdrinier 35 wire weaving looms require additional blows or beats of the reed relative to the shute or weft wires, in order to prevent said weft wires from rolling or turning or springing away from the proper position. The mechanism to be described 40 hereinafter obviates this difficulty.

In this connection it will be noted that the driven shaft 20 carries a small cam 28. Disposed below said cam 28 is a hydraulic dash pot which will be described in detail hereinafter, and 45 which is referred to generally by the numeral 29. Within said dash pot there is a plunger 30 carrying a roller 31 at its outer end, which roller is adapted to engage the cam 28. Depression of said plunger 30, by the cam 28, serves to open 50 a valve, permitting fluid to flow under pressure into a chamber 41 below a piston 32 due to a vacuum established by the piston in its raised position. The piston has an integral upwardly, outwardly projecting piston rod 33 pivotally connected to an end portion of a pair of links 34. The other end portion of the links are pivotally connected to the outer end of a lever 35 and the other end portion of said lever is mounted fast on the rocker shaft 24. Obviously the 55 rocking movement of said shaft 24 will transmit movement to the piston rod and piston.

Referring now particularly to Figs. 4, 5, and 6 of the drawings it will appear that the hydraulic dash pot 29 is illustrated in detail. Within one 60 side of the housing of said dash pot there is an oil reservoir 36 having a lower discharge port 37 controlled by a valve 38. Said valve is carried by an upwardly extending valve rod 39 which is guided by a wall portion 40 and the upper 65 end of said valve rod is surrounded by a coiled spring 42 confined between the top of said wall portion and adjusting nuts 43. The upper end of said valve rod engages the plunger 30 which is moved by contact with the cam 28, as previously explained. The cam 28, which is mounted

on the driven shaft 20, acts on the roller 31 and thereby, through the plunger 30 and valve rod 39, operates the valve 38 against the force of the spring 42. In actual practice the rocking shaft 24 completes a cycle of rocking or reciprocating motion while the driven shaft 20 makes one revolution. Hence, as will hereinafter appear, the piston rod 33 and the valve 38 can work in harmony.

In the lower portion of the casing of the dash 10 pot 29, and laterally removed from the valve 38, there is a valve seat 44 which also serves as a guide for a valve 45. Said valve 45 is urged to its lowered position by a spring 46. The valve 45 is mounted within a valve housing 47 and 15 has a sliding fit with respect thereto.

Within the lower portion of the housing 29 there is adjustably mounted a fluid flow control screw 48. Said screw is utilized to control fluid flow from the cylinder chamber 41 through ports 20 49 and into and through a ported plug 62 and vice versa, such flow being via ducts 49, 50, 51, 52 and chamber 53.

Directly below the cylinder chamber 41 there 25 is an opening 54 and said opening affords passage between the oil reservoir 36 and said chamber 41, by connecting at one end with a passage 55 which opens into the reservoir 36. Flow of fluid through the passage 55 is controlled by an operable control screw 56. Both the control screws 30 48 and 56 are suitably packed and mounted to prevent fluid leakage.

The valve 38 is formed with a valve seat 57 which partially receives another valve 58 adapted 35 to be yieldingly held against the valve seat 57 by a spring 59, which is mounted as shown in Fig. 4.

The operation of the hydraulic dash pot and the mechanism and valves therein, in conjunction with the other mechanism described, will 40 be understood from the following description: When the lay 8 drops by gravity to carry the woof wire 17 into position to form the cloth, the piston rod 33, through its connections with the lay, is moved from its lowered position to its raised position. This action of the piston rod, and the piston 32 carried thereby, causes a suction 45 within the chamber 41, lifting the valve 45 in opposition to the force of the spring 46. With said valve being open, and with a suction created, 50 fluid is drawn from or through the various ducts and ports previously described. The relief of pressure under valve 38 permits atmospheric pressure on the fluid in reservoir 36 to lower the valve 38 below and spacedly from a valve 55 seat 60 against the action of the spring 42. This opening movement of said valve 38 permits fluid from the reservoir 36 to flow through the opening 54 and into the cylinder chamber 41, filling 55 said chamber below the piston 32.

Immediately after the piston 33 reaches its 60 raised position, valve 45 closes in its housing 44 and against the valve seat formed therein. By virtue of an opening 61 provided in the housing 44, any fluid between the valve and its seat, is 65 forced out by the closing of the valve.

The rapidity with which the valve 38 is moved to closed position depends on the position or adjustment of the fluid control screw 48 since the movement of said valve is dependent upon the 70 rapidity of movement of fluid through the ducts 52, and the other ducts in communication therewith. However, until the valve 38 is closed against its seat 60, fluid in the chamber 41 is free to flow back into the reservoir 36. This action is, there- 75

fore, important in determining a partial down movement of the piston rod 33 and the rebound of the lay 8. If no rebound for the lay is desired, the control screw 48 must be adjusted so as to sufficiently open the passage 51 to permit a fast flow of fluid through the ported plug 62 to effect the immediate closing of the valve 38 against its seat 60.

On the other hand, operation of the loom may require no rebound to the lay, but a rearward creeping movement, instead. In this event the control screw 56 is adjusted so as to allow a slow flow of fluid through the passage 55 and eventually to the reservoir 36.

15 If it is desired to eliminate rearward creeping of the lay entirely, then the control screw 56 is adjusted so as to completely close the passage 55. This prevents any fluid from returning to the reservoir 36.

20 When the piston rod 33 is to move from its raised position to its lowered position, by reason of the action of the mechanism which returns the lay, cam 28 acts on the roller 31 to move the valve 38 away from its seat 60, thereby allowing fluid 25 to flow from the chamber 41, through the ducts and passages, and into the reservoir 36. There is pivotally mounted on the upper portion of the casing 29 a relief lever 63 integral with an extension lever 64. By this arrangement if the free 30 end portion of the lever 64 is manually depressed, it will push the plunger 30 downwardly and remove the roller 31 from contact with the cam 28. This, of course, will cause the valve 38 to open, and by means of said levers the machine operator 35 can reverse the movement of the lay temporarily, and at any time, irrespective of the normal movement imparted to the mechanism by the cam 28.

It is intended that valve 58 serve as a relief valve to eliminate undue pressure in chamber 41, 40 chamber 53, and the intermediate ducts when the valve 38 is opened quickly, and by virtue of the valve 58 fluid passes from the ported plug 62 through said valve 58, openings 65, and into the reservoir 36 until the film between the valve 38 45 and its seat 60 is broken. Valve 58 also serves as a safety valve in the event that cam 28 is set so that it will open the valve 38 slightly after the piston rod 33 has begun its downward movement.

Certain vents 66, extending between the upper 50 portion of the chamber 41 and the reservoir 36, serve to equalize the air pressure in said members 41 and 36.

It will thus be seen that by reason of the improved hydraulic dash pot in connection with the 55 lay operating mechanism, a desirable check is imposed on certain movements of the lay, heretofore unavoidable. The lay, through the connections described, operates in its normal manner, but undesired rebound thereof, after the reed 12 60 engages and moves the woof wires 17, is either eliminated or controlled, according to the desires of the operator. In other words, the improved dash pot supplies a controlled force in opposition to the normal rebound tendency of the lay.

65 By the adjustments and valve manipulations of the dash pot heretofore described the following alternative results are attainable:

1. Complete elimination of the lay rebound so as to hold the reed 12 firmly against the woof 70 wires 17 prior to or during a certain stage of the next operation of the heddle frames to cause a crossing over of the warp wires.

2. Replacement of the lay rebound by a plurality of vibrations or short blows of the reed 12 75 against the woof wire 17.

3. Regulation of the extent of the lay rebound so as to provide a desired amount of clearance between the reed 12 and woof wire 17.

In connection with the first result just mentioned, when the lay rebound is eliminated the 5 lay will be held so that its reed 12 engages and holds the woof wire 17 in against the wire cloth 18 until the woof wire is secured by being enclosed by the warp wires. Without this provision said woof wire will invariably rebound from the wire 10 cloth 18 after the lay has struck its blow. Under this condition when the warp wires close in on the woof wire, the latter will be carried forwardly by the next blow of the lay and cause serious 15 abrasion to the wires as well as undue disruption of the molecules of both the warp and woof wires, whereby the quality of the cloth will be impaired and its life will be shortened.

When the rebound is replaced by a plurality of vibrations or short blows the disadvantages just 20 mentioned are eliminated, and in addition a tighter cloth is formed.

Result #3 previously mentioned has the advantage of preventing rubbing of the reed against the woof wire in the event that there is a certain 25 amount of transverse motion of the woof wire relative to the reed. Obviously all of results 1, 2 and 3, previously enumerated, are for the purpose of making the mechanism flexible to meet different conditions of weaving in wire cloth. 30

From the foregoing description it will be obvious that the improved loom lay rebound control mechanism is of simple and novel construction, and is well adapted for the purpose described.

What is claimed as the invention is: 35

1. In a wire cloth weaving mechanism including a forwardly and rearwardly reciprocating wire engaging member, means for opposing the rebound tendency of said wire engaging member immediately following contact of the latter with 40 a resilient wire, and means to render the rebound opposer inoperative during the normal rearward reciprocation of the wire engaging member.

2. In a wire cloth weaving mechanism including a forwardly and rearwardly reciprocating wire 45 engaging member, means for controlling the rebound tendency of said wire engaging member immediately following its contact with a resilient wire, and means to render the rebound control inoperative during the normal rearward reciprocation of the wire engaging member. 50

3. In a wire cloth weaving mechanism including a forwardly and rearwardly reciprocating wire engaging member, adjustable means for opposing the rebound tendency of said wire engaging member 55 immediately following contact of the latter with a resilient wire, and means to render the rebound opposer inoperative during the normal rearward reciprocation of the wire engaging member. 60

4. In a wire cloth weaving mechanism including a forwardly and rearwardly reciprocating wire engaging member, mechanical means for opposing the rebound tendency of said wire engaging member immediately following contact of the latter with a resilient wire, and means to render the rebound opposer inoperative during the normal rearward reciprocation of the wire engaging member. 65

5. In a wire cloth weaving mechanism including a forwardly and rearwardly reciprocating wire engaging member, hydraulically controlled mechanical means for opposing the rebound tendency of said wire engaging member immediately following contact of the latter with a resilient 70 75

wire, and means to render the rebound opposer inoperative during the normal rearward reciprocation of the wire engaging member.

6. In a wire cloth weaving mechanism including a forwardly and rearwardly reciprocating wire engaging member, dash pot means for controlling the rebound tendency of said wire engaging member immediately following contact of the latter with a resilient wire, and means to overcome the restraint imposed by said dash pot means during the normal rearward reciprocation of the wire engaging member.

7. In a wire cloth weaving mechanism including a forwardly and rearwardly reciprocating wire engaging member, mechanical and hydraulic means for controllably opposing the rebound tendency of said wire engaging member immediately following contact of the latter with a resilient wire, and means for temporarily rendering said rebound control means inoperative during the normal rearward reciprocation of the wire engaging member.

8. In a weaving apparatus including a lay engaging warp and shute strands during weaving operations, means permitting forward and rearward reciprocations of the lay relative to one of the strands and into contact with said strand during the forward reciprocation, adjustable means connected with said reciprocating means for momentarily repelling undesired rebound of the lay following a contact with said strand, and means to render said rebound repeller inoperative during the normal rearward reciprocation of the wire engaging member.

35 9. In a weaving apparatus including a lay contactable with a shute strand during weaving operations, the lay being mounted for forward gravitation toward the shute strand and rearward reciprocation away therefrom, a rocker shaft, connections between the rocker shaft and the lay

for reciprocating the lay away from the shute strand following contact therewith, means connected with said rocker shaft for opposing rebound tendencies of the lay in the interim following its contact with the strand and just prior to the rearward reciprocation of the lay, and means for rendering said rebound opposer inoperative during the rearward reciprocation of the lay.

10. In a weaving apparatus including a reed carrying reciprocatory lay adapted to engage a taut shute strand during weaving operations, an oscillatory shaft, means in connection with said shaft and extending to the lay permitting gravitation of the lay into contact with said strand and then positive withdrawal from the same, and adjustable means connected with said shaft and partially controlled by movements of the same for temporarily repelling oscillation of said shaft to prevent rebound of the lay during the interval between its contact with the strand and its positive movement away therefrom.

11. In a weaving apparatus including a reed carrying lay adapted to engage a resilient strand during weaving operations, a rocker shaft, a cam shaft, a connection between the cam shaft and the rocker shaft for oscillating the latter, means permitting gravitation of the lay toward the resilient strand, connections between the rocker shaft and the lay for moving the latter away from the resilient strand, and adjustable check means connected directly with and interposed between the cam shaft and the rocker shaft for temporarily repelling oscillation of said rocker shaft to prevent rebound of the lay during the interval between its contact with the strand and its positive movement away therefrom.

JOHN D. WATSON.
